UNITED STATES PATENT OFFICE.

JAMES B. KENDALL, OF CHICAGO, ILLINOIS, ASSIGNOR TO NEWSTARTER MANUFACTURING COMPANY, OF CHICAGO, ILLINOIS, A CORPORATION OF ILLINOIS.

AIR-COMPRESSOR.

1,299,478.

Specification of Letters Patent. Patented Apr. 8, 1919.

Application filed September 17, 1917. Serial No. 191,812.

To all whom it may concern:

Be it known that I, JAMES B. KENDALL, a citizen of the United States, and a resident of the city of Chicago, in the county of Cook and State of Illinois, have invented a certain new and useful Improvement in Air-Compressors; and I do hereby declare that the following description of my said invention, taken in connection with the accompanying sheet of drawing, forms a full, clear, and exact specification, which will enable others skilled in the art to which it appertains to make and use the same.

My invention relates generally to improvements in air compressors; and it consists, essentially, in the novel and peculiar combination of parts and details of construction, as hereinafter first fully set forth and described and then pointed out in the claims.

The object of this invention is the production of an efficient, and serviceable air compressor, which, while adapted for general use, is more particularly designed for compressing air in self-starting devices for internal combustion engines, and which is especially well adapted for use in automobiles and motor trucks, and particularly, for that class of Ford cars, so called, which are not provided with self-starting means, but must be cranked to initiate the running of the motor.

This air compressor is of the two-stage, opposed cylinders type of machines; it is very compact, and can be sold at such a reasonable figure as to be an inducement to owners of motor vehicles not supplied with self-starters, to install this system in their cars.

In the drawings, forming a part of this specification, and which illustrate the preferred embodiment of my invention, Figure 1 is a longitudinal vertical sectional view of this air compressor, drawn on line 1—1 of Fig. 2. Fig. 2 is a longitudinal horizontal section of the same on line 2—2 of Fig. 1. Fig. 3 is an end elevation of the machine. Fig. 4 is a detached front elevation of the cylinder head applied to the first-stage, or large compression cylinder. Fig. 5 is a sectional view of the same on line 5—5 of Fig. 4. Fig. 6 is an end view of the same. Fig. 7 is a plan of the cylinder casting detached. Fig. 8 is a front elevation of the same. Fig. 9 is an end view of the smaller

cylinder end, and Fig. 10 is a like view of the larger cylinder end. Fig. 11 is a side view of the twin pistons detached. Fig. 12 is a plan of a portion of the same; and Fig. 13, is a sectional view on line 13—13 of Fig. 12. Fig. 14 is a longitudinal sectional view of the wrist-pin detached; and Fig. 15 is a transverse sectional view of the same, on line 15—15 of Fig. 14. Fig. 16 is a plan view of the cut-out mechanism of the machine. Fig. 17 is a side view of the same, partly in section. Fig. 18 is an inverted plan thereof; and Fig. 19 is a sectional view on line 19—19 of Fig. 17. Fig. 20 is an elevation of the wobbling disk employed in this device; and Fig. 21 is a sectional view of the same. Fig. 22 is a sectional view on line 22—22 of Fig. 23, of the clutch and driver sprocket wheel by which the compressor is started and stopped. Fig. 23 is an end elevation of the same. Fig. 24 is a sectional view of a fragment of the device illustrated in Figs. 16, 17, and 18, and showing the diaphragm by which the stopping of the compressor is accomplished. Fig. 25 is a plan of the same, a part being cut away to disclose underlying elements. Fig. 26 is a plan of the latch employed in this device. Fig. 27 is an end elevation of the right end thereof, and Fig. 28 is a sectional view of the same on line 28 of Fig. 26. Fig. 29 is an elevation on an increased scale, of a portion of the cylinder head of the second stage compression cylinder. Fig. 30 is a sectional view of the same on line 30—30 of Fig. 29. Fig. 31 is an inverted plan, and Fig. 32 is an edge view of the same. Fig. 33 is an end elevation of the compressor, illustrating its connection with the motor of a Ford car, the motor being illustrated rather diagrammatically and without reference to details of construction except such as are necessary to show this connection.

Like parts are designated by the same characters and symbols of reference in all the various figures.

The principal part of this machine comprises a casting having at one end the large, or first-stage compression cylinder A, and at its other end the smaller, or second stage compression cylinder B, both cylinders being axially aligned and separated by a chamber C, in which portions of the operating mechanism are located. In these cylinders there is movably located a twin piston,

comprising a central, cylindrical, portion 33, which is connected by oppositely extending, alined bars 35, one of which terminates in the smaller piston 36, and the other of which 5 terminates in the larger piston 37. The central, cylindrical portion 33 is provided with diametrically opposed, slotted apertures 38, the object of which will hereinafter appear. In the bore 39 of this cylindrical portion 10 there is rotatably fitted a wrist-pin 40, Figs. 14, and 15, which wrist-pin is transversely bored, as at 41, said wrist-pin having at its ends reduced portions which are externally screw threaded to receive flanged nuts 42, 15 so that when the wrist-pin has been inserted in the bore 39 of the cylindrical portion 34, the flanged nuts 42 will bear against the opposing faces of the cylindrical portion 33, and thereby securely retain the wrist-pin in position.

In the opposing side walls 43, 44, of the central chamber C, there are axially alined bearings 45, 46, and in these bearings there 20 is rotatably mounted a shaft 47, which I shall hereafter term the operating shaft, and which is best shown in Figs. 1, and 21. This operating shaft has its two ends screw-threaded to receive nuts 48, 49; and adjacent the locking nut 49 there is placed a 25 sleeve 50, which sleeve has one end externally screw-threaded, as at 51, and upon this screw-threaded portion 51, there is placed a driven sprocket wheel 52. Upon the shaft 47 there is secured an annular body 53, which will be hereinafter called the wabbling disk. This wabbling disk has a 30 cylindrical bore 54, to receive the operating shaft 47, and to which it is, preferably, fastened by a set screw 55. This bore 54 is inclined to the axial line of the body of the wabbling disk 53, whereby said wabbling disk receives its "throw." This cylindrical body 53 has on its periphery an annular flange 56, by which it is rotatably retained 35 in a cylindrical casing 57, which is bored as at 58, to receive one end of the wabbling disk 53; and this bore is then enlarged, as at 59, to permit the laterally extending flange 56 to enter said enlarged bore. This 40 latter bore is internally screw-threaded to receive a follower 60, which follower is an annular ring the bore of which receives the outer end 61, of the crank 53, while its inner flank bears an antifriction ring 62; there 45 being a like antifriction ring 63, interposed between said flange 56, and the bottom of the enlarged bore, to reduce friction as far as possible. In the outer flank of the follower 60 there are a series of notches or 50 grooves 64, which serve primarily as means for applying a spanner wrench to screw the follower into the casing 57, and then as a means to receive a wire loop 65, passed through a hole in the casing and entering 55 one of said notches 64, as clearly illustrated

in Figs. 20 and 21, to lock said follower to said casing 57.

On the casing 57, and radially extending therefrom, there is a pin 66, which pin, when the wabbling disk is mounted in the 70 chamber C, and the twin piston in position in the cylinders, engages the transverse hole 46 in the wrist-pin 40, to operate the pistons, as will hereinafter appear; and this pin also passes through the oblong apertures 75 38 in the central portion 33 of the twin pistons to reach the wrist-pin, and at the same time prevent the rotation of said twin pistons.

The operating shaft 47 with its wabbling 80 disk 53, and the casing 57 surrounding the same, are located in the chamber C, which, as shown in Fig. 8, has an open front through which the wabbling disk and its casing are introduced to the chamber C, 85 which front is closed by a plate 152, Fig. 3, fastened to the chamber C, by screws 153. By this construction the chamber C serves as an oil-reservoir to lubricate the parts in said chamber which lubrication is attained 90 by the rapid rotation of the parts therein splashing the lubricant all over the casing and reaching also the two cylinders A, B.

The larger cylinder A is closed by a cylinder head D, shown in detail in Figs. 3, 4, 95 5, and 6. This cylinder head is of oblong contour, as is also the flange 67 on the large cylinder; and on this cylinder head D there is integrally formed a tubular boss 68, 100 which has in its bore a ball, or other suitable valve 69, Fig. 2, retained upon its seat by a coil spring 70, the upper end of this bore 71, being internally screw-threaded and closed by a plug 72. The valve 69 normally closes a passage 73, leading to the 105 large cylinder A, and from the bore 71 leads an outlet passage 74. Through the cylinder head D there is drilled a hole 75; and surrounding this hole there are a series of intake holes 76. The central hole 75 has, in a recess in the back of the cylinder head, a valve seat 75^a, Fig. 5, upon which seats a valve 77, Fig. 2, the stem of which passes through the central hole 75 and extends beyond the face of the cylinder head D for some distance, and terminates in a fixed washer 78. A spiral spring 79 surrounds this stem of valve 77, and functions to keep the valve 77 normally upon its seat to close the inlet passages 76 in said cylinder head D. 110

The smaller cylinder B, is closed by a cylinder head E, of a construction illustrated in detail in Figs. 29 to 31 inclusive.

This cylinder head E comprises a preferably rectangular, plate 80, medially of 125 which there rises a boss 81, which boss has two bores, 82, and 83, there being in the bore 83 a valve seat 84, on which seats a ball valve 85, Fig. 2, normally held against the seat 84 by a spring 86, bearing at one 130

end against the ball valve 85, and at its other end against a nipple 87, in screw-threaded engagement with the bore 83.

In the bore 82 of the boss 81 there is a 5 valve seat 88, Fig. 30, against which seats a valve 89, Fig. 2, having its stem passed through a hole 90, there being on said valve stem a spiral spring 91, Fig. 2, which normally forces the valve 86 against its seat, 10 the end of the bore 82 being closed by a plug 92. From the boss 81 extends a tubular boss 93, the bore of which is closed by a plug 94, Fig. 30, engaging the internal 15 screw-threaded bore 95. This bore is in open communication with the bore 82 of the boss 81, and it has a side outlet 95^a, the object of which will now be described.

At the back of the cylinder casting A, B, 20 C, there is integrally formed a rib or projection 96, through which is drilled a passage 97, which reaches from the face of the large cylinder to the face of the small cylinder, and the side outlet 95^a, in the cylinder head E connects with this passage 97 at one 25 end, while the passage 73 in the cylinder head D, (Fig. 5) connects with said passage 97 at the other end. By these passages 74, 97, and 95^a, a direct communication between the cylinders A, B, is established past the 30 cylinders and the central chamber C.

Again referring to the cylinder head E, there is formed at the back of the plate 80, a rib 98, which terminates in a, preferably 35 rectangular, plate 99, standing at right angles to the plate 80; and through this boss or rib 98, and connecting with the boss 81, there is drilled a passage 100, which outlets in the face of the plate 99, as clearly illustrated in Figs. 29 and 31. To this plate 99 40 there is screwed, by screws 101, Fig. 1, an element F, Fig. 3, which I term the cut-out, detailed in Figs. 16 to 19 inclusive, and also in Figs. 24 and 25. This cut-out comprises a plate 102, which has screw holes for the 45 reception of the before-mentioned screws 101. In the face of this plate 102 there is a circular depression or recess 103, and a smaller recess 104, and finally an opening 105 through the remainder of the plate 102. 50 Connected to plate 102 is a bar 106, which terminates in a tubular boss 107, the bore of which is closed by a plug 108, Fig. 19. This tubular boss 107 connects with a second tubular boss 109, placed at right angles to 55 the boss 107, the lower end of which boss 109 is transversely slotted as at 110, Figs. 18 and 19. From the lower face of the plate 102 extend two lugs 111, which are punctured for the passage of a bolt 112, upon 60 which there is pivoted a bar 113, which will be hereinafter called the latch. This latch has near one end an adjusting screw 114, entering the hole 105 in the plate 102, which adjusting screw 114 is prevented from accidentally rotation by a set screw 115. In the 65

bore of the boss 107 there is located a coil spring 116, Figs. 18 and 19, which spring acts on the latch 113 to depress the same.

In the recess 103 in the plate 102 there is located a metallic diaphragm 117, Figs. 24 70 and 25; and below this diaphragm there is placed in the recess 104 a disk, which may be termed a follower, against which the adjusting screw 114 contacts, while the follower 118 bears against the under side of the diaphragm 117. Interposed between the diaphragm and the plate 99 and the plate 102, there are packing washers 119, to prevent air from escaping between the joints of these parts. 75

Referring to Figs. 7, 8, 9, and 10, there extends from the back of the cylinders A, B, two bars 120, 121, which bars are punctured at their ends as at 122, in which there is located a screw-bolt 123, to be hereinafter 80 again referred to. From the back of the chamber C extends a punctured lug 124, through which, and the bore of the boss 109 on the cut-out F, Fig. 17, there is passed a bar 125, at one end of which there is pivotally connected an operating lever 126, which, with its lower extremity bears against an abutment 127, Figs. 1, 17, and 19, formed on the boss 109 of the cut-out F, the other end of said lever being connected by means, not 85 shown, to any element which the operator of the car, or other motor-operated, vehicle can readily reach to manipulate this lever. The bar 125 is bent at right angles as shown in Fig. 2; and the terminal of this rod 125 ends 90 in a fork 128, in order to connect rod 125 to a driving mechanism 129, shown in detail in Figs. 22 and 23. This driving mechanism comprises, in the case where the compressor is attached to a Ford motor, an internally 95 screw-threaded socket 130, on which there is formed a cylindrical shank 131. On this shank there is rotatably mounted a driving sprocket wheel 132. In the hub of this sprocket wheel there are two, diametrically 100 opposite holes; and in the face of the socket 130 there are two corresponding recesses 133, 105 Fig. 22.

In front of the sprocket wheel 132 there is placed a disk 134, on which there is centrally formed a shank 135, and on this shank there is mounted a washer 136, spaced from the disk 134 to admit the fork 128 on the rod 125 between them. To this disk 134 are affixed two pins 137, which pass through the 110 hub of the driving sprocket 132, and normally enter the recesses 133 in the socket 130. When thus engaged, the socket 130 when rotating, communicates rotative movement 115 to the sprocket wheel by said pins, but when said rod 125 is free to move longitudinally in the direction shown by an arrow in Fig. 22, by a spring 138, surrounding said rod 125, the disk will draw the pins 137 out of the recesses 133 and thereby disconnect the 120 125

130

sprocket wheel from its driving element. By pulling the lever 126 in the direction indicated by an arrow in Fig. 1, the clutch disk 134 with its pins 137 may be moved to establish the connection between the driving element and the driving sprocket wheel. In order to hold this sprocket wheel in engaged position, there is formed, on the rod 125, a notch 139, Fig. 17, wherewith a notch 140, Fig. 26, in the latch 113 engages to hold the rod 125 in clutch-engaging position. To release this rod 125, and to disengage the clutch from the driving element 129, I employ the automatically operating device comprising the diaphragm and correlated parts as hereinbefore described.

The driving sprocket 132 is connected to the driven sprocket 52, on the crank shaft, by a link belt 141, as clearly shown in Fig. 33.

The operation of this air compressor, is essentially, as follows:

The driving sprocket 132 rotates the driven sprocket 52, mounted on the operating shaft 47, and this shaft rotates the wobbling disk 53, which, in turn, reciprocates the pin 66 on the casing 57 which surrounds the crank. This reciprocating movement is communicated to the twin pistons by the wrist-pin 40, with which the pin 66, entering the transverse hole 41 in said wrist pin, is connected. Air is drawn into the large cylinder A, through the opening of the valve 77, which air, on the return stroke of the pistons is compressed and expelled from the cylinder A by closing the valve 77 and opening the valve 69. This air, having received its first stage of compression, now passes through the passage 73 in the cylinder head D, and the passages 97 and 95^a, into the bore 82 and opening the valve 88, into the smaller cylinder B, from whence the air, in its second stage of compression, escapes, or is forced, by opening the valve 85, on the return stroke of the smaller piston to pass through the nipple 87 to a storage tank, not shown. There is in the exit passage 83 in the boss 81 of the cylinder head E, the small passage 100, which leads to the upper surface of the diaphragm 117; and as the air in the cylinder B is being compressed, this diaphragm will be downwardly depressed, moving with it the follower 118, which, acting through the adjusting screw 114 upon one end of the latch 113 and depressing the same, causes the other end thereof to rise and gradually move the latch 113 out of the notch 139 in the rod 125, so that, when the predetermined compression of air has been attained, the latch 113 will have released the rod 125, the spring 138 thereon will move the rod 125 longitudinally, and thereby disconnect the driving sprocket from the driving element, and thus stop the compressor. It may now

be noted that this stopping of the compressor is entirely automatic, as soon as the predetermined air compression has been reached, the degree of which can be regulated by the adjusting screw 114. This stopping cannot be controlled by the lever 126, which can only function to start the compressor, when desired, or when the pressure in the storage tank falls below the predetermined pressure, by manipulating the lever 126. Instead of connecting this automatically and manually operating means for starting and stopping the air compressor to the driving sprocket 132, I may provide the driven sprocket 52, on the operating shaft 47 with the clutch mechanism shown in Figs. 2, 22, and 23, in connection with the driving sprocket 132, and connect the rod 125 with its fork 128, to the driven sprocket, a change which would be a reversal of the order of arrangement, and as such, clearly within the scope of my invention. This change would probably be desirable in a case where the air compressor is more or less remotely located from the prime mover.

In the preamble to this specification I have stated that this air compressor is especially well adapted for use in a Ford car; and in Fig. 33 I have indicated how this air compressor can be connected to the motor of this, or any other car having the same, or a similar engine. This engine has a link 145, having at each end an eye, which link, at one end, engages the bolt 123 in the two rearwardly extending bars 120, 121, extending from the air compressor, the other end of said link engaging an element 146, on the motor casing through which the motor shaft to which the clutch mechanism is secured, is passed, thereby securing the air compressor to the motor M and affording one of the two connections of the air compressor to the motor M. On the back of the central portion of the cylinder casting there is formed a boss 142, which is tapped to receive a screw-eye 143, which engages a bolt 144 found on the motor M, thus forming a second, and adjustable, connection with the motor. This screw-eye 143 performs the additional function of serving as a means for taking up slack in the link belt 141, by unscrewing the screw-eye more or less, as the condition of the link belt may require. And it may here be stated that the bolt 123 serves as a pivot on which the air compressor may swing to permit of the adjustment of the link belt being made.

In order to take up wear or slack in the operating shaft 47, there are provided in the end of one or both of the adjusting nuts 48, 49, a series of notches 150, Fig. 3, wherewith the pin 151, passing through the shaft 47, may engage. By withdrawing this pin and rotating the nut, wear may be taken up,

and then the nut again secured against rotation, by inserting the pin to engage the nearest notch into which it will fit. And instead of a pin, or pins, I may use wire loops, such as are shown at 65, in Fig. 21, for this purpose. By means of the lateral movement of the operating shaft 47, I am, furthermore, enabled to so adjust the twin pistons that neither of said pistons can strike the respective cylinder head, said pistons being so constructed that there is, for well-known reasons, but a very limited clearance between the ends of the pistons and the cylinder heads. Thus, longitudinally moving the operating shaft, causes a corresponding movement of the twin piston, so that their proper location can, at all times, be maintained. This is a very important feature of my invention which positively avoids any knocking of the pistons against one or the other of the cylinder heads.

This machine operates perfectly noiseless and without jar, jolt, or knocking, so that it is especially well adapted for use in automobiles.

I have hereinbefore described with considerable minuteness the preferred embodiment of my invention, but I desire it to be understood that I am aware that many of the details of construction disclosed, may be varied, and parts omitted without departing from the scope of my invention as defined in the subjoined claims.

Having thus fully described this invention, I claim as new, and desire to secure to myself by Letters Patent of the United States—

1. The combination, with a motor, of an air compressor, said air compressor having two means for connecting the same to said motor, viz. a pivotal connection, and an adjustable connection, said connections comprising two bars and a boss projecting rearwardly from the air compressor, a bolt mounted in said bars, a link mounted at one end to said bolt and at the other end to an element on said motor to afford a pivoted connection between said air compressor and the motor, there being in screw-threaded connection with said boss a screw-eye, said screw-eye engaging a screw-bolt on said motor to afford adjustable means for connecting said air compressor to the motor for taking up slack in the connection between the driving element of the motor and the driven element of the air compressor, said motor having a driving element, and said air compressor having a driven element operatively connected to said driving element, manually operated means for initiating the operation of said air compressor, and automatically operated means for stopping the air compressor when a predetermined air compression has been attained.
2. In an air compressor, the combination,

including a substantially rectangular, box-like casing, said casing having at its upper end oppositely extending cylinders, said cylinders having differing bores, said cylinders being in axial alinement, an air conduit formed integrally with said cylinders and said casing and extending from the outer end of one cylinder to the outer end of the other cylinder, a twin piston in said cylinders, means for operating said pistons, a cylinder head at the outer end of one of the cylinders, said cylinder head having an inlet valve to admit air to said cylinder, said cylinder head having a tubular boss, a passage in said boss connecting said cylinder to one end of the aforesaid air conduit, a valve in said passage normally closing said passage, a second cylinder head at the outer end of said second cylinder, said second cylinder head having two tubular bosses, a branch leading from one end of said bosses, said branch having a bore connecting at one end with the other end of said air conduit and its other end with one of said tubular bosses, an inlet valve in the bore of the latter tubular boss permitting the admission of air from the first-named cylinder, an air valve in the second of said tubular bosses, a discharge nozzle leading from the second tubular boss, a downwardly extending tubular rib leading from the latter tubular boss, a flange in which the said tubular rib terminates, a second flange bolted to the first-named flange, a diaphragm interposed between these two flanges, and mechanism operable by the distention of said diaphragm for arresting the means for operating said twin piston.

3. In an air compressor, a casing, comprising a substantially rectangular casting, said casing being open at one side, said open side being closed by a cover bolted thereto, there being projecting from the flanks of said casing at the upper end thereof a pair of cylinders, said cylinders being in axial alinement, said cylinders being integrally formed with said casing, said cylinders being open at their inner and their outer ends, there being on said cylinders, and within said casing a rib formed integrally with said cylinders and the top of said casing, said rib extending from the outer end of one cylinder to the outer end of the opposing cylinder said rib having a bore to afford an air conduit, there being projecting from the lower ends of said flanks tubular bosses said bosses being axially alined and in parallel alinement with the axis of said cylinder, said bosses being constructed to afford bearings for an operating shaft traversing said casing.

4. In an air compressor, a casing, comprising a substantially rectangular casting, said casing being open at one side, said open side being closed by a cover bolted thereto,

said opening being large enough to permit operating mechanism to be inserted into said casing through said opening, there being projecting from the flanks of said casing at 5 the upper end thereof a pair of cylinders, said cylinders being in axial alinement, said cylinders being formed integrally with said casing, said cylinders being open at their inner and their outer ends, there being on 10 said cylinders a rib integral with said cylinders and extending from the outer ends of said cylinders to said casing, a continuation of said rib being formed integrally with the upper end of said casing, there being in 15 said rib a bore extending from the outer end of one cylinder to the outer end of the opposing cylinder, there being projecting from the flanks of said casing at the lower end thereof tubular bosses, said bosses being in 20 axial alinement and in parallel relationship to the axial line of said cylinders said bosses being constructed to afford bearings for an operating shaft traversing said casing, there being projecting from the upper rear 25 25 end of said casing two spaced apart bars, said bars being punctured at their ends to afford means for pivotal attachment of said casing, and from the lower end of said casing there being projecting an internally 30 screw-threaded lug to afford adjustable means for attachment of said casing to a supporting object.

5. In an air compressor, the combination, comprising, a box-like casing, cylinders projecting from the upper flanks of said casing in opposite directions, said cylinders being in axial alinement, bearings projecting from the lower flanks of said casing said bearings being in parallel alinement with said cylinders, a twin piston in said cylinders, a shaft rotatably mounted in said bearings and traversing said casing, mechanism for operatively connecting said shaft to said twin piston, and a conduit connecting the outer 45 ends of said cylinders, said conduit being integrally formed with said casing and said cylinders.

6. In an air compressor, the combination, comprising, a box-like casing, cylinders projecting from the upper part of the flanks of said casing in opposite directions, said cylinders being in axial alinement, a twin piston in said cylinders, bearings projecting from the lower part of the flanks of said 55 casing, said bearings being in parallel alinement with said cylinders, a shaft rotatably mounted in said bearings and traversing said casing, mechanism for operatively connecting said shaft to said twin piston, said mechanism comprising an annular hub, said hub being angularly disposed to the axial line of said shaft, said hub being secured to said shaft by a set screw, said hub having approximately medially a circumferential 60 flange, an annular, cup-shaped shell on said 65

hub, said shell having its bottom provided with a central bore, said bore embracing one end of said hub, the bore of said shell embracing the periphery of said flange, the open end of said shell being internally screw-threaded, a follower in said shell in screw-threaded engagement with the open end thereof, annular washers between the outer flank of said annular flange and the bottom of the shell, and between the inner flank 70 of said annular flange and the inner face of said follower, there being notches in the outer face of said follower, means on said shell and engaging said follower in said notches to prevent rotation of said follower, 75 said shell having an arm reaching to, and engaging said twin piston.

7. In an air compressor, the combination, comprising, a motor, clutch mechanism connecting said motor to the air compressor, a low pressure and a high pressure cylinder, said cylinders being axially alined, a twin piston reciprocatively mounted in said cylinders, means for reciprocating said twin piston, manually operated means for initiating the operation of said piston, and automatically actuated means for arresting the operation of said piston, the latter means including a cylinder head at the end of the high pressure cylinder, said cylinder head having a discharge passage leading from said high pressure cylinder, a valve in said discharge passage closing said air passage during the suction stroke of said high pressure piston, a chamber comprising two elements, one of said elements being integrally formed with said cylinder head, there being in said element a passage connecting said element with said discharge passage, said second element having in its face an annular depression, said depression having a central through-opening, said second element having downwardly extending punctured lugs, a diaphragm interposed between said two elements, said diaphragm being normally in an upwardly distended condition, a lever pivotally mounted in said lugs, a follower below said diaphragm, said lever having means passing through said through-opening to act upon said follower to sustain said diaphragm in upwardly distended condition, and means operatively connected to said lever and said clutch mechanism for disconnecting said motor from said air compressor when said diaphragm is downwardly distended by air pressure acting upon said diaphragm.

8. In an air compressor, the combination, of a casing, said casing including two axially alined cylinders, a twin piston in said cylinders, cylinder heads at the outer ends of said cylinders, said casing having laterally extending, axially alined bearings, an operating shaft rotatably mounted in said bearings, a wobbling disk fixed to said operating shaft, said wobbling disk being op- 120 125 130

eratively connected to said twin piston, and means for longitudinally adjusting said operating shaft, said operating shaft having externally screw-threaded ends and a hole 5 transversely therethrough, a nut upon each screw-threaded end, the outer face of each nut having radially disposed notches, and pins in said holes and engaging said notches, whereby the position of the twin piston in 10 said cylinders may be adjusted to afford proper clearance between the outer ends of the pistons and said cylinder heads.

9. In an air compressor, the combination, of a motor, clutch mechanism connected to 15 said motor, and an air compressor operatively connected to said clutch mechanism, said air compressor including a low pressure and a high pressure cylinder in axial alinement, a twin piston reciprocatively 20 mounted in said cylinders, means for operating said twin piston, manually operated means for operatively connecting said operating means to said clutch mechanism, and automatically operating means for disconnecting said operating means from said 25 clutch mechanism, the latter means includ-

ing a rod, one end of said rod being operatively connected to said clutch mechanism, the other end of said rod having a notch, a spiral spring on said rod said spring being tensioned and acting on said rod to move the clutch mechanism out of engagement with said motor, a chamber connected to said high pressure cylinder, a diaphragm in said chamber, a lever pivotally connected to 30 said chamber, one end of said lever being connected to said diaphragm to hold said diaphragm normally in upwardly distended condition, the other end of said lever normally engaging the notch in said rod and 35 holding the clutch mechanism in operative engagement with said motor, said manually operated means including a lever at the end of said rod constructed to move said rod longitudinally to cause engagement of said 40 clutch mechanism with said motor after having been disconnected therewith by said automatically operating mechanism.

In testimony that I claim the foregoing as my invention, I have hereunto set my 45 hand.

JAMES B. KENDALL.
